United States Patent Office

Des. 185,586

Patented June 23, 1959

185,586

COMBINED CLEANING BRUSH AND CUTTING TOOL

Earl S. Tupper, Smithfield, R.I., assignor to Tupper Corporation, North Smithfield, R.I., a corporation of Delaware

Application November 20, 1957, Serial No. 48,565

Term of patent 14 years

(Cl. D9—2)

Figure 1 is a view in perspective of a combined cleaning brush and cutting tool, embodying my new design;

I claim:

The ornamental design for a combined cleaning brush and cutting tool, substantially as shown and described.
